H. CORRALL & J. M. FORBES.
SEWING MACHINE.
APPLICATION FILED FEB. 9, 1914.

1,241,710.

Patented Oct. 2, 1917.

UNITED STATES PATENT OFFICE.

HERBERT CORRAL, OF HELENSBURGH, AND JAMES MOIR FORBES, OF SCOTSTOUN, GLASGOW, SCOTLAND, ASSIGNEES TO THE SINGER MANUFACTURING COMPANY, A CORPORATION OF NEW JERSEY.

SEWING-MACHINE.

1,241,710.

Specification of Letters Patent.

Patented Oct. 2, 1917.

Application filed February 9, 1914. Serial No. 817,458.

To all whom it may concern:

Be it known that we, HERBERT CORRAL and JAMES MOIR FORBES, subjects of the King of the United Kingdom of Great Britain and Ireland, and residing at Helensburgh, Dumbartonshire, Scotland, and Scotstoun, Glasgow, Scotland, respectively, have invented certain new and useful Improvements in Sewing-Machines, of which the following is a specification.

This invention relates to embroidery sewing machines, and has for its object to provide simple and effective means for governing the number of stitches to be formed by a train of machines, the mechanism including means for stopping the machines with a minimum shock to the driving elements and while the needle of each unit is above the work.

The improvements are especially adapted for use in conjunction with a series or train of embroidery sewing machines arranged to operate simultaneously in connection with moving work-holders controlled by a man-

ually-actuated pantograph device, as disclosed in our Patent No. 1,159,901, dated November 9, 1915. The mechanism includes a bracket provided with an integral oil chamber which receives a helical gear-wheel fixed

to the main-shaft of a sewing machine and engaging a like gear-wheel upon a shaft extending transversely of said oil chamber and rotating within bearing bosses provided by the bracket. Fixed upon the outer end of the latter shaft is a driven wheel or friction disk provided with a projecting hub upon which is slidably mounted a driving-wheel adapted to be thrown into engagement with the friction disk but normally pressed out of

engagement therewith by a coiled spring within said projecting hub. A plural armed rock-lever is employed to throw the driving-wheel into and out of operative engagement with the friction disk and also to apply a

brake to the latter when it is released. To stop the friction disk in such position that the needle is above the work and to absorb the shock produced by the sudden arrest of the disk the latter is provided with two

springs contained within a chamber concentric with its hub, each spring being connected to a pin secured to a collar loosely mounted upon and normally rotating with the hub of the disk. When the rock-lever is

actuated to release the disk from contact with the driving wheel, a trip or stop element carried by said lever locks the aforesaid collar against movement, whereby the momentum of the disk is taken up by the compression of one spring and the expansion of the second spring, in conjunction with the action of the brake element carried by said lever. The rock-lever is operated by a bell-crank provided with a roller which engages the point of a pin secured to a projecting arm of the lever, the bell-crank being connected to the upper end of a rod secured at its lower end to a treadle device. By such arrangement the operator has positive control of the driving elements, and by movement of the bell-crank from one extreme position to the other can cause the machines to be stopped automatically at the termination of each stitch; or by movement of the bell-crank to mid-way position and in constant engagement with the rock-lever can cause the machines to produce stitches uninterruptedly.

In the accompanying drawings Figure 1 is a side elevation, partly in section, of the present improvements, and Fig. 2 is a plan view, partly in section, of the same. Fig. 3 is a perspective view of the plural armed rock-lever, and the driven wheel or disk, showing the latter in section. Fig. 4 is a perspective view of the collar and of the trip element. The invention is shown applied to a sewing machine 1, comprising the first of a train of embroidery machines, supported upon a table or stand 2, the work-holder 3 of the machine being adjustably connected to a supporting bar 4 to which movements are imparted by means of the pantograph 5. The main-shaft 6 of the sewing machine is provided with a helical gear 7 which is received within an oil chamber 8 formed integrally with a bracket 9 secured to the sewing machine standard by means of screw 10, said oil chamber being provided with a removable cap 11 pivotally secured to the bracket by means of stud screw 12. At opposite sides of the oil chamber are formed bearing bosses 13 and 13^x to receive a shaft 14 extending transversely of the oil chamber and supporting the helical gear-wheel 15 which engages the like wheel on main-shaft 6 of the sewing machine. In the present instance boss 13^x is enlarged to conform

with the diametrical proportion of the hub 16 of a driven wheel or friction disk 17 fixed upon shaft 14 by means of screw 18. The hollow hub 16 of friction disk 17 projects beyond the end of shaft 14, thus providing a chamber 19 to receive a coiled spring 20 which rests between the end of shaft 14 and the head of a pin 21, the latter being pressed upon the hardened steel cap 22 of driving wheel 23 which is loosely fitted upon the said projecting hub of the disk. The spring 20 acts normally to disengage the face of driving wheel 23 from contact with a ring 24 of leather or the like fitted 15 within an annular groove formed in the inner face of the friction disk. The driving wheel 23 is provided with the usual peripheral groove 25 to receive driving belt 26 which in practice is driven by a motor or 20 other power device.

In the present instance bracket 9 is provided with a laterally projecting foot 27 which serves as a support for the plural-armed operating rock-lever 28, said lever being pivoted upon the bracket foot by means of a stud screw 29 which enters an aperture formed within the hub 30 of said lever, the enlarged head of screw 29 serving to confine upon said hub the sleeve 31 of a brake-arm 32 provided with a brake-shoe 33 adapted to contact with inclined surface 34 upon friction disk 17, said surface constituting a stop element for the disk. The brake-arm 32 rests upon the end of a screw 35 adjustable 30 within boss 36 upon one arm *b* of the rock-lever 28.

The arm *a* of the rock-lever is enlarged at its extremity and provided with a socket to receive a spring-pressed plunger-pin (such 40 as shown at 82, Fig. 1 of the patent to Barron, No. 998,595) having a rounded head 37 which is disposed adjacent the cap 22 of driving-wheel 23. It will be seen that the movement of rock-lever 28 to the left from the position shown in Figs. 1 and 2 will carry the plunger pin away from the driving wheel, thus permitting spring 20 to move said wheel out of operative engagement with the disk 17, it being apparent that 45 such movement of the lever will carry brake-arm 32 in position to engage inclined surface 34 of the driving-wheel. The reverse movement of the lever 28 will move the driving wheel 23 axially against the action 50 of spring 20 whereby the face of the driving-wheel will be brought into frictional engagement with ring 24 upon the disk and rotary movement will be transmitted to said disk and the main-shaft 6 of the sewing machine.

To stop the friction disk at a given point and to absorb the shock produced by the sudden arrest thereof, the disk is provided with coiled springs housed within an annular chamber 38 surrounding its hub, said

chamber being closed by cap 38^x. One end of each spring 39 is connected to a pin 40 secured to the disk, and the opposite ends of the springs are connected to a pin 41 projecting within annular chamber 38, said pin 70 passing through a concentric slot 42 formed in the disk 17 and being fixed to the flange 43 of a collar 44 loosely mounted upon the hub 16 of said friction disk and normally rotating therewith. The flange 43 of said collar is cut away to provide a gap and opposed shoulders 43^x. When lever 28 is rocked to stop the machine a trip or stop element 45 upon arm *b* of the rock-lever enters the gap formed in the flange of collar 44 and engages one of the shoulders 43^x, whereby the collar is held against rotation and the momentum of the friction disk is overcome by the compression of one spring and the expansion of the second spring aided 80 by the action of brake-arm 32.

The operating means for rock-lever 28 comprises a bell-crank 46 pivoted by means of screw stud 47 to a bracket 48 secured to the table or stand 2, said bell-crank being provided with a roller 49 adapted to engage the point of a pin 50 secured to the outer extremity of the arm *c* of lever 28. The bell-crank is freely connected, by means of a usual universal joint such as disclosed in 90 the patent to Diehl *et al.*, No. 997,376, to the upper end of a rod 51 similarly connected at its lower end to a treadle device 52 of any suitable construction. A spring 53 secured to the table and connected to the rock-lever tends to tilt the latter to carry arm *a* 100 out of engagement with the driving wheel and the brake and trip elements into engagement with the friction disk. It will be seen that the bell-crank 46 in its mid-way position, shown in Figs. 1 and 2, will hold arm *c* of the rock-lever elevated and the driving wheel in operative engagement with the driven wheel and thus will effect a continuous operation of the machine while it 105 remains in such position. To start the machine and cause it to be stopped automatically at the termination of each stitch-forming operation, the bell-crank 46 is moved from one extreme position to the other 110 whereby the roller 49 engages the pin 50 on arm *c* of the lever 28, and causes the spring plunger carried by arm *a* to engage the cap 22 on the driving wheel 23 which is thus moved axially against the action of 115 the spring 20 so that its face is brought into engagement with the ring 24 upon the friction disk 17 and thereby rotates said disk and the shaft 14. On the said upward movement of the arm *c* the brake shoe 33 is disengaged from the driven wheel 17 and the trip element 45 on the arm *b* is disengaged from the gap portion of the flange collar 44, remaining in disengaged position until 120 the wheel 17 has made one complete revolution. 125

tion and the gap again comes into register with the trip element 45 which is thereupon moved into the gap by the action of the spring 53, the brake shoe 33 being simultaneously applied to the wheel 17, whereby further rotation of said disk is prevented to arrest the main-shaft in the sewing machine head, the adjustment of the parts being such that the needle carried by the needle-bar on the machine is clear of the work.

It will be understood that the transverse shafts 14, which transmit motion to the main-shafts 6 of the train of machines, may be connected by means of coupling-bars 53* or by similar means, and that various changes may be made in the construction and arrangement of the parts, it being manifest that the invention is not limited to the precise embodiment thereof herein shown and described.

Having thus set forth the nature of the invention, what we claim herein is:—

1. The combination with a train of embroidery sewing machines, a series of work-holders, a pantograph and a bar connecting said work-holders and pantograph, of a rotatable shaft and connections between said shaft and said machines for actuating all said machines in definitely timed relation to each other, frictional driving means under the control of the operator for initiating at will the simultaneous operation of all of said machines, and mechanism including braking means, whereby all of said machines may be arrested at a predetermined period in the cycle of their operations after the completion of each stitch, or may be arrested at such period after the completion of any desired number of stitches.

2. The combination with a plurality of embroidery sewing machines, each machine including a main-shaft, of a rotatable shaft separate from but having operative connec-

tions with the main-shafts of the machines for actuating said machines in definitely timed relation to each other, friction clutch elements adapted when engaged to cause rotation of said rotatable shaft, and means under the control of the operator adapted to effect engagement of said clutch elements, and to disconnect said clutch elements and arrest the rotation of said shaft at a predetermined period in the cycle of operations either on the production of a single stitch or on the production of any desired number of stitches.

3. The combination of a train of embroidery sewing machines, a series of work-holders, a pantograph and a bar connecting said work-holders and pantograph, of a rotatable shaft and connections between said shaft and said machines for actuating all of said machines in definitely timed relation to each other, driving means, a starting and stopping device connecting said driving means with said rotatable shaft, means including a treadle-controlled rock-lever for controlling the action of said starting and stopping device, and operative connections between said rock-lever and starting and stopping device whereby the movement of said rock-lever from either of its extreme positions to the other will initiate the formation of one complete stitch by each machine and cause said machines to stop at a predetermined period in the cycle of their operations.

In testimony whereof we have signed our names to this specification in the presence of two subscribing witnesses.
